2,602,965

FALLER BAR SHOCK ABSORBER

Richard G. Denton, Jr., Cleveland, Ohio, assignor
to The Warner & Swasey Company, Cleveland,
Ohio, a corporation of Ohio

Application February 5, 1949, Serial No. 74,737

10 Claims. (Cl. 19—129)

1

This invention relates to gill boxes containing pin drafting mechanism for the treatment of slivers or fibers as a part of the yarn making process, and more particularly to shock absorber means for absorbing the energy imparted to the faller bars during the transfer operation and for stabilizing the motion of the faller bars as they are picked up by the lead screws.

Gill boxes have been proposed wherein one or two sets of faller bars are advanced with the sliver by cam or screw means, transferred at the end of their drafting stroke to return lead screws of a relatively high pitch by a rotary S-cam, and transferred by another S-cam to their drafting position. Modern weaving and drafting machinery is operated at speeds higher than those formerly encountered in the art. The increase in speed has accentuated difficulties and problems incident to the operation of gill boxes of the type to which this invention relates.

One of the difficulties encountered is in connection with the faller bars. The pins of such bars are customarily made separately and fastened in place in the bars by means of soldering, crimping, or other fastening operations. With the increased speed of operation mentioned, the bars are rapidly projected by the S-cams against their guide strips or saddles at the ends of each transfer operation. The impact of the faller bars against their guides or saddles tends to loosen the pins from their mounting so that after a period of time the pins become detached from the bars, greatly reducing the uniformity of the drafting action. Likewise, the impact of the bars against their saddles or guides tends to deform, dent, or wear the guides at the point of impact, and after a period of operation the deformation resulting tends to cant the bars as they are picked up by the associated lead screws. This canting of the bars in the lead screws also reduces the uniformity of the drafting action and impairs the entry action of the pins into the sliver. Although these effects can be reduced by reducing the speed of the apparatus, such an expedient is not desirable because not only does it reduce the output of the apparatus, but the faller bar pins do not make as clear an entry when the machine is run at low speeds as it does when the machine is run at higher speeds.

I am aware that certain proposals have been made to provide some sort of spring or relief means for lessening the shock or impact of the bars during transfer. However, prior relief means have been unsatisfactory in that they have been either weak and ineffective in their action, have had too much mass to be effective cushions, or

2

have been cumbersome and complicated, thereby introducing additional sources of mechanical difficulty.

It is an object of the present invention to provide effective cushioning that prevents detachment of the pins from the bars, protects the saddles or guide members from deformation, and does not interfere with effective transfer action, the cushioning means being extremely simple to manufacture and inexpensive to maintain. Briefly, this is accomplished by providing low-mass, resiliently-extended plungers which receive the impact of the bars and retract into their housing readily, to permit the normal motion of the bars to occur. Preferably, the plungers are extended by a resilient rubber-like body of material which absorbs the energy of the bars without excessive rebound, and provides a smoothly-acting and rugged cushioning means.

Another difficulty encountered, particularly when the speeds of the gill boxes are increased over the prior practice, is that the action becomes erratic at the phase in the transfer cycle wherein control of the bars shifts from the S-cam to the lead screw or faller bar advancing means. There is a period wherein the S-cam loses control of the bars and wherein the bars have not fully engaged the lead screw, and during this period canting, pounding, and slapping of the bars may readily result.

An important object of the present invention resides in resiliently gripping and guiding the bars during this period to produce a uniform and steady action. This is accomplished by providing saddle or guide cam surfaces which face and cooperate with the cushioning means so that the bars are resiliently gripped and firmly guided during the aforesaid transition period until the bars are substantially fully engaged with their lead screws, at which time the problem is no longer present.

Ancillary objects reside in providing cushioning means that are readily installed in existing machines that provide virtually no interfering parts to catch dirt, lint, or the like, that can be readily replaced, and that are economical to manufacture and install.

The manner in which these and other objects that will be apparent to those skilled in the art are obtained will be apparent from the following detailed description of a preferred embodiment of the invention.

In the drawings:

Fig. 1 is an end view of a typical gill box embodying the invention;

Fig. 2 is a longitudinal section thereof;
Figs. 3 and 4 are fragmentary sections illustrating the operation of the device;

Figs. 5 and 6 are partial views showing typical faller bar construction;

Fig. 7 is a detail of the buffer assembly with the cover plate removed; and,

Fig. 8 is a section taken on 8—8 of Fig. 7 with the cover plate in place.

Referring to the drawings, the gill box 10 includes several conventional elements known to those skilled in the art which will not be described in detail. These elements are the lower return screw and shaft 11, the lead screw and shaft 12 for the lower set of bars, the lead screw and shaft 13 for the upper set of bars and the upper bar return screw and shaft 14. The return and lead screws are geared together for opposite rotation and the pairs of screws are also geared together for synchronism by suitable gearing well known in the art.

S-cams 15 are provided to transfer the faller bars, the construction and operation of these cams being well known in the art. As in the usual construction, S-cams are carried at the sliver exit ends of the lead screws to transfer the bars to the return screw, and at the sliver entrance end of the apparatus S-cams are carried by the return screws to transfer the bars to the lead screws.

In the preferred form the faller bars B are arranged in upper and lower sets. First support means or saddles 16 guide the bars of the lower set as they are advanced during drafting. Second support means or saddles 17 support and guide the bars as they are returned by the lead screws 11 to the entrance end of the apparatus. Similarly, there are provided first support means or saddles 18 to guide the upper set of bars during drafting, and second support means or saddles 19 which support them during their return motion.

Each bar member B includes the usual pins 21 that are soldered or otherwise fastened in place. Each bar is relieved as at 22 for pin clearance between the rows of bars. The ends of the bars are formed with screw followers as at 23 to ride in the screws, the followers 23 preferably being arranged so that the bars are vertical when the followers are disposed in the lead screw or means that advances them for drafting. Opposite ends of the bars are notched as at 24 to assist in guiding them over the ends of the saddles during transfer from one screw to the other.

As disclosed in the co-pending application of James R. Longstreet and Raynaldo Jacques, Serial No. 41,646, filed July 30, 1948, resiliently mounted guiding fingers or conductors are provided to assist in the smooth transfer action at both ends of the apparatus. For the lower set of bars there is an outer conductor 26 for guiding the bars during transfer to the return screw and an inner conductor 27 for guiding the bars during transfer to the lead screw. Similarly, conductors 28 and 29 respectively are provided for the upper set of bars. Certain features of construction are common to all conductors and will be described in connection with finger 26. The fingers are pivotally mounted on the frame of the apparatus as at 31 and carry a spring bolt 32 which mounts a spring 33 reacting against a block 34 fixed to the frame of the apparatus. A stop 35 may be provided to limit the action of the spring on the finger. The function of the

conductors is described in detail in the aforesaid co-pending application of Longstreet et al., Serial No. 41,646.

Although buffer or cushioning means formed in accordance with the invention may be disposed wherever impact of the faller bars becomes a problem, the most critical location is where the faller bars are transferred from the return screws into their drafting position. That is where they are forced into or make entry with the sliver. This position of the cushioning means is illustrated in detail in the drawings. The guides or saddles 18 are substantially in the plane of the sliver; their upper surfaces guide the upper set of faller bars during the drafting operation and their lower surfaces prevent displacement of the faller bars from the normal position and engagement against the upper surfaces of the saddles 16.

As seen in Figs. 2, 3, and 4, cushioning means are mounted behind cover plate 39 in the entrance end of the saddles 18. As seen in Figs. 7 and 8, recesses 41 are sunk in the ends of saddles 18 and oppositely extending holes 42 are broached to intersect the recesses, these holes being square in the preferred embodiment. Disposed in each recess is a block of rubber-like material 43 which may be relieved as at 44 to increase its resiliency. A pair of oppositely extending square plungers 46 have their shanks disposed in holes 42 and are formed with pads 47 that bear against the rubber-like block 43. Each plunger 46 is beveled as at 48 to facilitate the sliding of the faller bars over the plunger. The parts are arranged so that the rubber body 43 is deformed upon impact of the faller bar against the plunger and absorbs the energy of the faller bar, preventing it from striking either surface of the saddles 18. The clearance between the walls of recess 41 and the rubber-like body, coupled with the presence of aperture 44 in the body, provide two columns of rubber-like material with a space at each side thereof to accommodate flow of the body material under impact of the faller bars. Since the plungers, which may be made of hardened and tempered steel, are readily removable by removing the screws 40 that retain the cover plate 39, they are made to assume all the wear resulting from the impact of the faller bars and the saddles will last indefinitely.

As best seen in Figs. 3 and 4, the plungers cooperate with cam surfaces on certain of the saddles to perform a novel and highly desirable function. For example, in the lower left portion of Fig. 3 one of the lower faller bars is in a position wherein it is no longer being lifted by the S-cam, but has just been picked up by the associated lead screw for drafting motion. The guide for saddles 16 is beveled as at 16a to form a cammed surface so that as the lead screw picks up and advances the faller bar, its vertical motion or entry into the sliver is completed by a camming action of surface 16a, which also serves to firmly set the followers 23 of the bar in the threads of the lead screw. During the camming action however, the followers are not firmly seated in the lead screw, nor are they under control of the S-cam during which period slapping, canting, and jarring of the bars might occur were it not for the novel cooperation of the associated buffer plungers and the cam surfaces.

For example, the lower bar in Fig. 3 has just been picked up by the lead screw and is resili-

iently, but firmly, gripped between the lower resiliently extended plunger 46 and the facing surface 16a on the saddles 16. This resilient gripping action continues until the faller bars are virtually completely seated in their screws. A transition from the engagement of the bars with the plungers 46 and with their guiding surfaces is made smoothly by means of the beveled edge 48 of the plungers. A similar cam surface 19a is formed in the saddle 19. This cam surface need not be as long as the cam surface 16a because in the case of the upper bars gravity assists the entry of the bars into the sliver, whereas it opposes that entry with the lower bars. Nevertheless, there may be a transition period like that described and the plungers and cam surfaces cooperate to firmly guide and locate the bars during that period. Of course, if difficulty is encountered at the exit end of the apparatus, suitable cushions may be mounted above and below the bars as they are transferred from the lead screws to the return screws.

It will be understood that the various design details of the buffer assembly may be modified without departing from the essence of the invention or the action of the assembly in the combination, but the preferred construction embodies a rubber-like body for expelling the plungers mounted in the saddles as shown. Although the preferred construction is one wherein the plungers are vertical, i. e. parallel to the transfer motion of the faller bars, it will be understood that this angle may be varied so long as the cushioning action is not made excessively stiff or hard.

It will also be understood that although a preferred embodiment of the invention has been illustrated and described, the appended claims and not the aforesaid embodiment are determinative of the scope of the invention.

What is claimed is:

1. In a gill box, a series of faller bars, faller bar advancing means for causing said bars to traverse with a sliver, return screws for engaging the ends of the bars, saddles for guiding the bars during their traverse with a sliver, cam means for transferring said bars from the return screws to said faller bar advancing means, cam means for transferring said bars from the advancing means to said return screws, and cushioning means carried by said saddles for receiving said bars during transfer, said cushioning means comprising a base having a chamber, a plunger normally projecting from said chamber above the surface of said saddles and a body of rubber-like material in said chamber and tending to project said plunger, said body of rubber-like material comprising at least one column of rubber-like material for supporting said plunger, there being an open area to each side of said column to facilitate flow of the material of the column during engagement of the saddles by the bars during transfer.

2. In a gill box, a series of faller bars, faller bar advancing means for causing said bars to traverse with a sliver, return screws for engaging the ends of the bars, saddles for guiding the bars during their traverse with a sliver, cam means for transferring said bars from the return screws to said faller bar advancing means, cam means for transferring said bars from the advancing means to said return screws, generally vertical bores in said saddles intersecting a chamber formed therein, plunger means in said vertical bores and normally projecting above the surface of said saddles having

of said saddles, and a body of rubber-like material in each chamber engaging the inner end of said plunger means and tending to project said plunger means for receiving the impact of the faller bars during transfer.

3. In a gill box, a series of faller bars, faller bar advancing means for causing said bars to traverse with a sliver, return screws for engaging the ends of the bars, saddles for guiding the bars during their traverse with a sliver, cam means for transferring said bars from the return screws to said faller bar advancing means, cam means for transferring said bars from the advancing means to said return screws, generally vertical bores in said saddles intersecting a chamber formed therein, plunger means in said vertical bores and normally projecting above the surface of said saddles, and a body of rubber-like material in each chamber engaging the inner end of said plunger means and tending to project said plunger means for receiving the impact of the faller bars during transfer, said plungers being beveled in the direction of travel of said bars thereover to guide said bars gently against the saddles.

4. In a gill box, an upper and lower series of faller bars, faller bar advancing means for each series for causing said bars to traverse with a sliver, return screws for each series for engaging the ends of the bars, saddles for guiding the bars during their traverse with a sliver, cam means for transferring said bars from the return screws to said faller bar advancing means, cam means for transferring said bars from the advancing means to said return screws, upper and lower generally vertical bores in said saddles intersecting a central chamber, plunger means in said vertical bores and normally projecting above and below the surfaces of said saddles, and a body of rubber-like material in said chamber engaging the inner ends of said plunger means and tending to project said plunger means for receiving the impact of the faller bars during transfer.

5. In a gill box having a series of faller bars, faller bar advancing and return means, and cam means for transferring said bars to and from the return screws, buffer means for receiving the faller bars during transfer comprising a housing, a bore in said housing intersecting a chamber formed therein, plunger means in said bore and normally projecting above the surface of said housing, and a body of rubber-like material in said chamber engaging the inner end of said plunger means and tending to project said plunger means for receiving the impact of the faller bars during transfer.

6. In a gill box having a series of faller bars, faller bar advancing and return means, and cam means for transferring said bars to and from the return screws, buffer means for receiving the faller bars during transfer comprising a housing, oppositely extending generally vertical bores in said housing intersecting a chamber formed therein, plunger means in said generally vertical bores and normally projecting above the surface of said housing, and a body of rubber-like material in said chamber engaging the inner ends of said plunger means and tending to project said plunger means for receiving the impact of the faller bars during transfer.

7. In a gill box, a series of faller bars, faller bar advancing means for causing said bars to traverse with a sliver, return screws for engaging the ends of the bars, first saddles having

guide faces for guiding the bars during their traverse with a sliver, second saddles having guide faces for guiding said bars during their return motion, transfer cam means for transferring said bars from the return screws to said faller bar advancing means, cam means formed on said saddles and arranged to gradually move said bars in a vertical direction toward the guide faces upon which they rest during their drafting motion, and cushioning means carried by said gill box for engagement by said bars, said cushioning means comprising opposed metallic plungers and a block of rubber-like material disposed between the inner ends of said plungers tending to project said plungers toward said saddle cam means, said plunger and saddle cam means being arranged to resiliently grip said faller bars between them during their period of initial engagement with said faller bar advancing means and after they have been released by said transfer cam means, said block of rubber-like material comprising at least two rubber-like columns extending between the plungers there being a free space for flow of the material at each side of the columns.

8. In a gill box, an upper and a lower series of faller bars, each faller bar having a comb portion and guide portions at the ends thereof, faller bar advancing means for each series for causing said bars to transverse with a sliver, an intermediate pair of laterally spaced saddles disposed to each side of the path of the sliver through said gill box, upper and lower pairs of laterally spaced saddles, each pair being spaced from said intermediate pair by a distance substantially equal to the width of said faller bar guide portions to form faller bar receiving channels, said faller bar advancing means being co-extensive with said channels, return screws above and below said upper and lower pairs of saddles, transfer cam means for transferring said faller bars from the return screws to said faller bar advancing means, cam means formed on the under end portion of said upper pair of saddles and on the upper end portion of said lower pair of saddles at the sliver entrance end of the gill box, said cam means being arranged to gradually move said bars in a vertical direction toward said intermediate pair of saddles, oppositely extending members mounted on said intermediate saddles and extending toward said cam means, and means resiliently urging said members toward the opposed cam means, the spacing between the ends of said members when fully extended and the opposed cam means being less than the width of said faller bar guide portions

whereby said members and cam means resiliently grip said guide portions as the faller bars enter said channels.

9. In a gill box having a series of faller bars, faller bar advancing and return means, and cam means for transferring said bars to and from the return screws, buffer means for receiving the faller bars during transfer comprising a housing, a vertical bore in said housing intersecting a chamber formed therein, plunger means in said vertical bore and normally projecting above the surface of said housing, and a body of rubber-like material in said chamber engaging the inner end of said plunger means and tending to project said plunger means for receiving the impact of the faller bars during transfer, there being a space between each side of said body and the wall of said chamber to accommodate flow of the material of said body during transfer.

10. In a gill box having a series of faller bars, faller bar advancing and return means, and cam means for transferring said bars to and from the return screws, buffer means for receiving the faller bars during transfer comprising a housing, a vertical bore in said housing intersecting a chamber formed therein, plunger means in said vertical bore and normally projecting above the surface of said housing, and a body of rubber-like material in said chamber engaging the inner end of said plunger means and tending to project said plunger means for receiving the impact of the faller bars during transfer, there being a space between each side of said body and the wall of said chamber to accommodate flow of the material of said body during transfer.
